CLAIM

We claim the ornamental design for a snip, as shown and described.

DESCRIPTION

FIG. 1 is a front perspective view from above of the claimed design;

FIG. 2 is a left side view of the claimed design of FIG. 1; FIG. 3 is a right side view of the claimed design of FIG. 1; FIG. 4 is a front side view of the claimed design of FIG. 1; FIG. 5 is a rear side view of the claimed design of FIG. 1; FIG. 6 is a top view of the claimed design of FIG. 1; and, FIG. 7 is a bottom view of the claimed design of FIG. 1. Any portion of the article depicted in broken lines forms no part of the claimed design. Broken lines formed by equal length dashes show unclaimed portions of the design.

1 Claim, 5 Drawing Sheets
